UNITED STATES PATENT OFFICE.

HARRY S. GOVER, OF BEL AIR, MARYLAND.

STREET-RAIL SLEEPER.

1,103,761.

Specification of Letters Patent. Patented July 14, 1914.

Application filed April 7, 1914. Serial No. 830,182.

To all whom it may concern:

Be it known that I, HARRY S. GOVER, a citizen of the United States, residing at Bel Air, in the county of Harford and State of Maryland, have invented certain new and useful Improvements in Street-Rail Sleepers, of which the following is a specification.

My invention relates to new and useful improvements in sleepers for supporting the rails of street railways in paved streets and resides in the provision of simple and inexpensive means which partly incases and supports the rails in such a way that spreading or creeping of the rails is prevented and protection of the greater portion of the rails against the elements is provided.

An important object of my invention is to provide a sleeper of the character described which consists of channel shaped casings in which the rails are mounted and which are provided with angle iron bars that clamp the rails upon opposite sides of the tops thereof, said sleepers being provided with transverse connecting bars to extend transversely of the rail beds and which strengthen and hold the sleepers in proper position.

Another important object of my invention is to provide sleepers of the character described which are arranged to be mounted upon a suitable foundation and that are simple as to construction, reliable and efficient in operation, arranged so that one rail section may be removed without disturbing the remainder of the track and which is inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a fragmentary perspective view showing my improved sleepers in operative position and the rails and sleepers in section, and Fig. 2 is a fragmentary plan view partly in section showing the sleepers in assembled operative position and supporting rails.

Referring to the drawings by characters of reference the numerals 1 and 2 designate the rails of a track for a street railway.

The rails 1 and 2 are designed to be supported by sleepers designated 3 as an entirety and of my improved construction. The sleepers 3 are mounted upon suitable foundations 4 and may be secured thereto if desired in any suitable manner.

I provide transverse connecting bars 5 that are secured at their ends to the sleepers 3 and arranged transversely of the road bed or track. These connecting bars 5 are provided with right angularly bent terminals 6 through which suitable fastening means are inserted to secure the bars 5 to the sleepers 3. My improved sleeper is formed in the nature of a channel shaped metal casing and comprises a bottom wall 7 and opposite side walls 8 and is open along its upper edge. The rails 1 and 2 are mounted within the sleepers 3 so that their bases rest upon the bottom wall 7 of the sleepers. In this connection it will be noted that the sleepers 3 are of just sufficient width to enable the rails to be placed therein thus providing a tight fit regarding the bases of the rails and sleepers and preventing lateral movement of the rails to a certain extent. The side walls 8 of the sleepers are disposed in a plane just below the tops of the rails.

As a means for clamping the rails I provide angle iron bars 9 that are secured within the sleepers and arranged to engage the heads of the rails upon opposite sides thereof. One angular extension of the angle bars 9 is disposed in a vertical plane and in engagement with the inner face of each of the side walls 8 and secured in such a position by bolts 10 or other suitable fastening means which will enable the detachable securing of the angle bars 9. The other angular extensions of the angle bars are disposed in a horizontal plane flush with the upper edges of the side walls and at their free edges engage opposite sides of the heads of the rails. To provide rigidity, strength and insure the clamping action of the angle bars 9 with relation to the rails I provide long bolts 11 that are inserted transversely through the side walls 8 and central portions of the rails 1 and 2. The bolts 11 extend outwardly from the side walls 8 and have nuts 12 turned thereon. By adjustment of the nuts the clamping action of the angle bars 9 may be regulated.

It will be readily seen that I have provided a novel means for supporting and incasing the street rails in such a way that

only the necessary portions of the rails are exposed and in such a way that spreading or creeping of the rails is prevented. It will be readily seen that with my improved device, a street cross over for railways may be provided.

In practice, I have found that the form of my invention, illustrated in the drawings and referred to in the above description, as 10 the preferred embodiment, is the most efficient and practical; yet realizing that the conditions concurrent with the adoption of my device will necessarily vary, I desire to emphasize the fact that various minor 15 changes in details of construction, proportion and arrangement of parts may be resorted to, when required, without sacrificing any of the advantages of my invention as set forth.

20 What is claimed is:—

1. In a sleeper for street railways comprising a channel shaped metallic casing designed to receive a rail so that the head of the rail is disposed above the sides of said casing, angular clamping members mounted within said sleeper arranged to engage opposite sides of the top of a rail and means extending transversely through the sides of the sleeper to adjust the clamping action of said clamping members.
2. In a device of the character described, the combination with a support of rails, elongated casings having open upper edges and comprising bottom and side walls, said rails to be mounted within the casings, transverse connecting bars connecting the casings with each other, means mounted within the casings to clamp opposite sides

of the tops of the rails, said means closing said casings, bolts inserted transversely 40 through the sides of the casings and central portions of the rails and nuts turned upon the ends of said bolts.

3. In a device of the character described, the combination with a foundation of elongated casings, rails to be mounted in spaced parallel relation to each other and within said casings and having their tops disposed slightly above the level of the edges of the sides of said casings, angle bars mounted 45 within said casings and secured interiorly of the side walls thereof adjacent the upper edges thereof to clamp the opposite sides of the tops of the rails, said angle bars having body portions thereof that clamp the rails disposed in a horizontal plane and flush with the upper edges of the side walls 50 of the casings, means connecting the casings with each other and means extending through the rails and casings transversely 55 to adjust the clamping action of said angle bars.

4. A sleeper for street railways comprising a channel-shaped casing designed to receive a rail so that the head of the rail is disposed above the side of the casing, rail clamping members mounted within the casing and arranged to engage opposite sides 60 of the top of a rail, and means to secure the casing to the rail.

In testimony whereof I affix my signature in presence of two witnesses.

HARRY S. GOVER.
